UNITED STATES PATENT OFFICE.

JOSEPH MAYHEW AND EDGAR D. PAYNE, OF CINCINNATI, OHIO.

HOISTING-MACHINE.

SPECIFICATION forming part of Letters Patent No. 277,147, dated May 8, 1883.

Application filed February 5, 1883. (No model.)

To all whom it may concern:

Be it known that we, JOSEPH MAYHEW and EDGAR D. PAYNE, citizens of the United States, residing at Cincinnati, county of Hamilton, 5 State of Ohio, have invented certain new and useful Improvements in Hoisting-Machines, of which the following is a specification.

This invention relates to that class of hoisting-machines which are used in the construction of new buildings for the elevation of brick, mortar, and other building materials. Its object is a cheap, compact, portable machine, which can be readily set up for use and quickly adapted to the different stories of the building, as the requirements demand.

The invention will be first fully described in connection with the accompanying drawings, in which similar reference-letters indicate like parts wherever they occur in the different views, 20 and then particularly pointed out in the claims.

Figure 1 is a vertical section taken through line *x x* of Fig. 2, showing in the rear of the drums and their operating mechanism two platform-elevators with hod-rests working between vertical guides, and suspended from ropes, which pass from the drums over pulleys hung in frames resting upon the joists of the story above. Fig. 2 is a top plan view of the driving mechanism.

Referring to the parts, A is a wooden frame, which forms the base of the machine. Upon the cross-tie A' is secured a standard or hollow pillar, B, which has projecting centrally from it a shaft, b, upon which the master-wheel C is journaled. Two standards, D D, secured upon the side timbers of the base A, furnish journal-bearings for the outer ends of the shafts e e', upon which the rope-drums E E' are secured. The inner ends of the drum-shafts are 35 journaled in a support, F, which arches over the master-wheel, and has its ends resting upon and secured to the base-frame. Upon the shaft e is secured a pinion, G, which meshes into the teeth of wheel C. A similar pinion, G', 40 is fitted to turn freely upon shaft e', and also meshes into wheel C, and is driven by it.

H is a clutch splined upon shaft e', and adapted to be thrown into or out of engagement with the pinion G' by a lever, h, ful- 45 crumed on the standard D. The object of the

clutch is to regulate the machine for elevating to the different stories of the building, as will be hereinafter described.

The drum-shafts are driven in opposite directions by the wheel C through the pinions 55 G G'. Motion is imparted to wheel C through a beveled pinion, J, which is secured upon the end of a shaft, j. The shaft j is driven by a cog, K, which is secured upon the crank-shaft k, and meshes into a pinion, L, secured upon 60 shaft j. The shafts j and k are journaled in a standard, M, which is secured upon the base A. The platforms N, having hod-rests n secured upon them, are arranged to slide between upright guides n', and are suspended from wire 65 ropes O O', which are wound in opposite directions around the drums E E', and pass over sheaves o, which are suspended from cross-bars in the frames P, which rest upon the rafters of one of the upper floors of the building.

The machine as represented in Fig. 1 is arranged to elevate to the second story of a building, the platforms being so adjusted that one is ascending while the other is descending. When, in the course of construction of the building, it is desirable to elevate the materials to the third story, the clutch H is thrown out of engagement with the pinion G'. The frames P are then placed upon the next tier of rafters above and the ropes O properly adjusted, 75 which is done by winding the rope upon the tight pulley until the platform sustained by it is brought to its upper position. The platform, which is suspended from the rope upon the now loose drum, being at the same time in its 80 lower position, the clutch is then thrown into engagement with the pinion G', and the machine is ready for use. The platforms are locked in any position by a pawl, q, thrown into engagement with a notched disk, q', keyed upon 85 the shaft j.

It will be seen that our machine can be cheaply constructed, occupies but a small space, and can be rapidly put up for use, changed for the different elevations required, and taken apart 90 for removal.

What we claim as new, and desire to secure by Letters Patent, is—

1. In a hoisting-machine of the character described, the combination, substantially as 100

specified, of frame A and master-wheel C with rope-drums E E', mounted upon shafts e e', and pinions G G', meshing into wheel C.

2. The combination of the rope-drums E E', 5 having pinions G G' upon the ends of their shafts at opposite ends, with the master-wheel C, arranged to engage the pinions G G' and rotate the shafts in opposite directions, and suitable mechanism, such as shown, to drive the master-wheel, substantially as described.

3. In a hoisting-machine of the character described, the combination, substantially as specified, of wheel C, drums E E', pinions G G', and clutch H, the pinion G being keyed to its 15 shaft, while the pinion G' is loose upon its shaft when the pinion G' is disengaged from

the clutch for the purpose of adjusting the machine to elevate at different heights.

4. The combination, substantially as specified, of the wheel C, mounted to rotate in a 20 horizontal plane, the rope-drums E E', having pinions upon the opposite ends of their shafts to engage with wheel C and rotate the drums in opposite directions, with mechanism to drive the master-wheel, and the platforms N N, frames 25 P, and ropes O.

JOSEPH MAYHEW.
EDGAR D. PAYNE.
